UNITED STATES PATENT OFFICE.

ERNST LEWERENZ, OF UTICA, MICHIGAN.

SUPPORT FOR CURTAIN AND DRAPE RODS.

1,088,430.

Specification of Letters Patent.

Patented Feb. 24, 1914.

Application filed September 16, 1913. Serial No. 789,966.

To all whom it may concern:

Be it known that I, ERNST LEWERENZ, a citizen of the United States, residing at Utica, in the county of Macomb and State 5 of Michigan, have invented certain new and useful Improvements in Supports for Curtain and Drape Rods, of which the following is a specification.

This invention relates to improvements 10 in supports for curtain and drape rods and its object is to produce such a support formed of a single piece of metal stamped in blank and then adapted to be folded or bent into shape and attached to the molding 15 ing by screws or other suitable supports when it will readily receive and retain both a curtain and a drape rod.

With the foregoing and other objects in view the invention consists in the combination 20 and arrangement of parts to be herein-after fully described in the following specification, pointed out in the claims and illustrated in the accompanying drawing which forms a part of said specification and in 25 which—

Figure 1 is a plan of the strip of metal from which my improved device is made. Fig. 2 is a side elevation of the same in use. Fig. 3 is a front view of Fig. 2. Fig. 4 is 30 a view of Fig. 5, in use. Fig. 5 is a plan of Fig. 3.

Like reference characters indicate corresponding parts throughout the several views.

35 I form my improved curtain and drape rod holder of a single piece of metal 1 which approaches the rectangular in shape but one end of which is somewhat wider than the other. In the relatively wide end 40 I make two incisions 2, 2 between the inner ends of which a neck 3 is formed which then connects the head portion 4 with the body portion 5. In the head 4 I cut a U-shaped slot 6 thus forming a tongue 7 in 45 said head and in the adjacent end of the body portion I provide the screw holes 8 to accommodate the screws by which the device is to be secured to the molding.

At or about the transverse center of the 50 blank strip of metal upon an imaginary line 6, 6 the blank is to be bent so that the portions of the body above and below said

line shall be disposed at right angles to each other as shown in Fig. 2. In the body portion below the line 6, 6 which is the narrow portion of the strip a small U-shaped slot 9 and a relatively large U-shaped slot 10 are formed, the ends of the two slots being disposed adjacent each other and between the slots 9 and 10 the tongues 11 and 12, respectively, are formed in the metal.

After the metal has been bent upon the line 6—6 as above described the head 4 is bent at right angles to the body portion 5 upon the neck 3 and said head is then 65 rounded into approximately semi-circular form and the tongue 7 is bent toward the free ends of the head from which ends it is equidistant. The free end of the lower or narrow portion of the strip of metal is now 70 rounded as shown at 13 and the tongue 12 bent up toward the portion 13 forming a semi-circle and the tongue 11 bent up between the last two named members. The curtain rod A is adapted to be inserted in 75 the curved head 4 of the strip and said rod is slotted to permit insertion therein of the tongue 7 of said head by which said rod is retained in position and the drape rod B is adapted for insertion between the members 80 12, 13 of the strip and is slotted to permit engagement with the tongue 11 of said strip, the rod A resting upon the drape rod B.

What is claimed is—

1. A curtain and drape rod support comprising a single strip of metal somewhat rectangular in shape and formed with a narrow extremity and a relatively wide extremity, a head formed in the wide end of said strip, a neck connecting said head and 90 strip, a tongue formed in said head and adjacent tongues formed in the narrow end of said strip, said tongues having their free ends remote from each other.

2. A curtain and drape rod support comprising a single strip of metal bent at right angles to itself and having one curved termination, a head formed at the opposite termination of said strip rounded to form a semi-circle disposed in a plane at right 100 angles to the plane of that termination, a tongue formed in said head bent at right angles to the same, tongues formed in the curved termination of said strip, one of said

tongues being curved to form a semi-circle with said termination and the other tongue being bent up at right angles to said strip and disposed equidistant from the ends of 5 the said semi-circle.

In testimony that I claim the foregoing as my own I have hereto affixed my signa-

ture in the presence of two subscribing witnesses.

ERNST LEWERENZ.
